UNITED STATES PATENT OFFICE.

BENJAMIN T. ANFIELD, OF BOULDER, COLORADO.

DRILLING APPARATUS.

Application filed January 25, 1927. Serial No. 163,436.

This invention relates to an improved drilling apparatus adapted especially to operate as a coal or rock drill, and it has more particular reference to a structure of this character which includes a drill carrying screw and an electric motor drive therefor.

An important feature of the improved structure is a novel differential feed device including a longitudinally movable drill carrying screw.

Another feature of construction is a sectional bushing employed for operating the screw and associated with means controlled by a brake bar for opening and closing the sections of the bushing to allow positive feeding of the screw or free adjusting movement as may be desired.

Another feature of construction is the compact and convenient motor drive including a controlling clutch.

A further feature of construction, is the novel supporting device which includes a frame and an adjustably mounted carriage upon which the drill proper is rockably mounted.

Other structural features and advantages of the invention will become apparent from the following description and drawings.

In the accompanying drawings forming a part of this application and in which like numerals are employed to designate like parts throughout the same:

Figure 1 is a longitudinal section through a drill constructed in accordance with the invention.

Figs. 2, 3 and 4 are cross sections taken approximately upon the planes of the lines 2—2, 3—3, and 4—4 of Fig. 1.

Fig. 5 is a perspective view of one of the details.

Fig. 6 is a fragmentary perspective view of a portion of one of the feed bushing sections.

Fig. 7 is a view showing the supporting frame structure.

Fig. 8 is a fragmentary view of the same structure showing the arrangement of details more plainly.

Fig. 9 is a perspective view of a part which cooperates with the parts shown in Fig. 5.

Fig. 10 is a side elevation of the complete structure, showing the external configuration thereof.

Fig. 11 is a view like Fig. 4, showing the sections of the bushing disengaged from the drill screw.

Fig. 12 is a perspective view of the nut operating gear.

Referring first to Fig. 10, it will be seen that the reference character 1 designates the casing of a suitable electric motor, associated with an appropriately constructed housing for the mechanism which includes the central section 2, a right hand end section 3, and a similar left hand end section 4. Carried by, and extending outwardly from the center of the central section 2 are supporting pintles 5 which serve a purpose to be hereinafter described.

Referring now to Fig. 1, it will be seen that the electric motor shaft is designated by the reference character 6, and that it serves to drive two separate gear trains. The left hand train comprises a relatively large gear 7 in mesh with the rotatably mounted idler 8, which is in turn in mesh with a clutch gear 9. The remaining train comprises a gear 10 meshing with a relatively small idler 11, which in turn is in mesh with a comparatively large gear 12.

All of these gears are of a size to provide the desired ratio. As before indicated, the gear 9 has operating connection with a normally closed clutch generally indicated by the reference character 13. This clutch includes operating pins 14 connected to a slidably mounted disk 15 operated by a similar and slidably mounted plate 16. Coiled springs 18 surround the pins 14 and bear at one end against an outstanding flange carried by a rotatably mounted sleeve 19.

This sleeve 19 is provided with internal keys 20 having driving connection with the multiple screw 21. As before stated, this screw carries the drill (not shown). It will be noticed in connection with the parts under consideration, that a suitable thrust bearing including anti-friction balls is interposed between the outstanding flange and the clutch and driving gear. Moreover, the tension of the springs 18 is such as to maintain the clutch normally closed. For the purpose of disengaging the clutch, I provide an operating frame 22 of the construction shown in Fig. 2, this being pivotally mounted on the depending lugs 23 on the casing structure and including an operating handle 24, by

means of which it is rocked back and forth. The arms of this frame are connected with the shifting plate or ring 16.

Referring now to the opposite end of this structure, it will be seen that the screw 21 extends thru duplicate half sections 25 of the split bushing. In this connection, it will be noticed that a pair of rods 26 and 27 are provided and connected at one end with the hub of the aforesaid gear 12. One section of the bushing in each instance, is pivotally or swingably connected with one of these rods 26 or 27 as shown better in Fig. 1.

The opposite ends of these rods connect with a ring 28 (see Fig. 9), which is journaled for rotation in the casing section 3 as represented in Fig. 1. In this connection, it will be noticed that the feed bushing which has screw threaded connection with the screw 21 is interposed between the hub of the gear 12 and the inner side of the rotatable ring 28. Also the rods 26 and 27 provide a driving connection whereby all of these parts are rotated as a unit. Since the gears 10, 11 and 12 serve to drive the bushing and as they are of different proportions with respect to the gearing train including the gears 7, 8 and 9, it is obvious that the screw 21 rotates at one speed and the bushing at a different speed, providing a differential action, thus causing the drill which is on the screw, to enter the work for boring in the customary manner, while simultaneously fed against the work, as the hole is bored.

As before stated, novel means is provided whereby the sections of the bushing may be disengaged from the feed screw. For instance, as shown in Fig. 4, these sections are engaged with the screw to produce the aforesaid differential operation. In Fig. 11, however, the sections 11 are swung away and disengaged from the screw to allow free rotation. The means under consideration comprises a brake bar 30 (see Fig. 1), which is movably mounted in the lugs 31 and which is operated by a manually rotated bolt 32.

This bar serves to engage a pair of annular bands 33 and 34, the first named of which surrounds the hub of the gear while the second one of which surrounds the periphery of the ring 28. In connection with the latter element, it will be noticed that this is provided with a pair of segmental projections 35 spaced apart and adapted to receive therebetween the sectors 36 carried by the band 34. In this connection, it is to be stated that the hub of the gear 12 is also provided with a pocket for reception of the corresponding sectors carried by the band 33. This arrangement allows the band to be shifted with respect to the parts on which they are mounted. In each instance, the sectors 36 are provided with cam grooves 37 for reception of operating fingers 38 of angular construction carried by the section 25 of the bushing.

With this arrangement it is obvious that by turning the bolt 32 inwardly, the bar 30 will be engaged with the bands 33 and 34, in order to temporarily hold them against rotation. Under ordinary conditions, the bands 70 rotate with the units by which they are carried. However, by stopping the rotation temporarily, it is obvious that the continued rotation of the complementary parts will cause the sections 25 of the bushing to move from the closed position represented in Fig. 4 to the open position represented in Fig. 11, due to the cam connections of the fingers 38 in the cam grooves 37 in the sectors 36, (see Fig. 4 in particular).

In this connection, it will be noticed that the aforesaid pins 26 and 27 are surrounded by coiled springs 39 provided at one end with small tubular anchors 40 (see Fig. 6), which are provided with teeth in engagement with serrations 41 provided on the aforesaid sectors 35, (see Fig. 9 and Fig. 1). The opposite ends of the springs bear upon the sections of the bushing as represented in Fig. 4, for the purpose of closing these sections, and maintaining them in closed relationship. Whenever it is desired to tension the spring, this is done by turning the anchors 40 in an obvious manner.

Confining attention now more particularly to Figs. 7 and 8 it will be seen that a supporting structure for the drill is here shown, and this includes a stationary frame 43 of vertically elongated form having an extensible anchor 44 at the bottom and the stationary anchoring projection 45 at the top. A carrier 46 is slidably mounted on this frame, and is adjusted up or down thru the medium of the intermeshing gears 47 and 48, the crank handle 49, the rack teeth 50, and 105 pawl and ratchet mechanism.

As shown better in Fig. 8, the top structure of this slideable carrier is formed with opposite seats 51 rotatably receiving the diametrically opposite pintles 5 carried by the central portion of the drill housing. This allows the entire drill to be rocked about the pintles and to be elevated up or down to the desired plane of operation. In order to hold it in various inclined positions, or level, as desired, I provide a lever 52 pivotally mounted on the housing carrying a binding shoe 53. Operating in conjunction with the levers 52 is a U shaped yoke 54 which is adjusted through the medium of a nut 55 mounted on a screw threaded stem 56 depending from the sections 4 of the housing.

The structure also includes appropriate enclosures for the gearing as well as switch boxes and wiring for the motor.

From the foregoing description, it is obvious that when the motor shaft 6 is set into rotation, the two separate gearing trains operate through different ratios to drive the sleeve 19 and its screw 21 at one speed, and 130

the split bushing at a different speed. Thus while the drill is boring, it is automatically fed at a desirable speed against the work to insure a continuous boring operation.

5 It is believed that by considering the description in connection with the drawings, a clear understanding of the construction and operation of the drill, as well as the supporting, adjusting and retaining means, 10 will be understood. In view of this, a more lengthy description is thought unnecessary.

Minor changes in the shape, size and arrangement of parts may be resorted to without departing from the spirit of the invention 15 or the scope of the appended claims.

Having thus described my invention, what I claim as new is:—

1. In a structure of the class described, a casing, gearing train including a gear provided with an outstanding central hub, a ring rotatably mounted in said casing and spaced from said hub, a split bushing interposed between said ring and hub, a drill screw extending thru the said gear, bushing 20 and ring, said bushing being provided with screw threads connected with the threads of said screw, connecting pins between the ring 25 and

and hub of said gear, the sections of said bushing being rockably mounted on said pins. 30

2. In a structure of the class described, a casing, gearing train including a gear provided with an outstanding central hub, a ring rotatably mounted in said casing and spaced from said hub, a split bushing interposed between said ring and hub, a drill screw extending thru the said gear, bushing and ring, said bushing being provided with screw threads connected with the threads of said screw, connecting pins between the ring and hub of 40 said gear, the sections of said bushing being rockably mounted on said pins, annular bands surrounding the hub and ring respectively, said bands being provided with inwardly directed sectors provided with cam grooves, 45 and cam fingers on the ends of the sections of the bushing in said grooves, together with means for temporarily holding said bands against rotation, to bring about a cam operation for disengaging the sections of the bushing from the threads of the screw. 50

In testimony whereof I affix my signature.

BENJAMIN T. ANFIELD.
